UNITED STATES PATENT OFFICE.

MARTIN M. DUX, OF NEW YORK, N. Y.

DESIGN FOR AN ADVERTISING-CARD.

SPECIFICATION forming part of Design No. 15,985, dated March 24, 1885.

Application filed January 16, 1885. Term of patent 7 years.

To all whom it may concern:

Be it known that I, MARTIN M. DUX, of the city, county, and State of New York, have invented and produced a certain new and original Design for Advertising-Cards, of which the following is a specification.

The design relates to advertising-cards.

The accompanying illustration is a front view of an advertising card or device embodying my design.

A designates an advertising card or device, here shown as having near its lower end flaring portions *a*, which curve inwardly and downwardly from each side toward the bottom of the figure and terminate in a squared end or portion, *a'*. Above the flaring portions *a* the body of the figure has side edges, *b*, which are slightly curved upwardly for a distance. Above the edges *b* are hollowed-out portions *c*, and above the portions *c* are squared portions *d*, the edges of which are on an up-

ward and inward incline. At the top of the figure and between the portions *d* is another hollowed-out portion, *e*. Upon the body of the figure appears a fanciful design, here shown as a vine, and about the edges of the portions *a*, *a'*, *e*, *d*, and *c*, I have shown a representation of a rope or cord.

B designates a representation of a receptacle for liquor, wine, beer, or other liquid. It is delineated as arranged upon the figure A.

What I claim as my design, and desire to secure by Letters Patent, is—

The design for an advertising-card of substantially the shape shown, having the representation of a bottle delineated thereon, as shown and described.

MARTIN M. DUX.
